PRINTING PRESS

Henry A. Wise Wood, New York, N. Y., assignor to
 Wood Newspaper Machinery Corporation, New
 York, N. Y., a corporation of Virginia

Application March 5, 1931, Serial No. 520,292
 Renewed May 21, 1935

8 Claims. (Cl. 270—5)

The present invention relates to web printing presses and particularly to a novel combination of single impression and multiple impression printing mechanism.

5 An object of the invention is to provide a novel means for printing a web in one color on one face and in a plurality of colors on the other face.

In my copending application, Serial No. 512,029, filed January 29, 1931, I describe the combination of a single impression perfecting press unit and a multiple impression unit, both adapted to print the same web, but in such a manner that the web will be printed in one color, say black, on each face thereof, and also in a plurality of colors on one of said faces.

15 The present invention provides a variation therefrom in the form of a unit comprising a single printing couple which prints one face of the web, while a set of plate cylinders with a single impression cylinder therefor, prints the other face of the web.

20 Another object of the invention is to provide a plurality of such units with means for collecting webs printed thereby and feeding the webs to a single folder.

25 Another object of the invention is to provide means for reversing the lead of a web through a unit whereby the multi-color impressions may be made on one or the other face of each web, as desired.

30 With these and other objects in view, I shall now describe an embodiment of my invention and thereafter will point out the novelty and scope of the invention in the claims.

35 The accompanying drawing shows a diagrammatic side elevation of a web printing press comprising a plurality of printing units each having a single impression and a multiple impression printing set together with means for varying the 40 lead of the web through the units.

The printing press illustrated in the drawing comprises a bed plate 19' on which are mounted a number of printing couples G and H, only two of which are shown in the drawing. Directly 45 above these units are mounted multiple impression sets M and N. The printing couple G comprises an impression cylinder 30 and plate cylinder 31, the latter being inked with an inking system 32. The multiple set M comprises an impression cylinder 33 with which cooperates a set 50 of plate cylinders 34, 35, 36 and 37. Each of the latter plate cylinders is provided with its own inking system 38. The printing couple H is substantially identical with the printing couple G and the multiple sets M and N are substantially 55 alike.

A web g is led from a roll 40 over a guide roll 41 to the right of the printing couple 30—31, as viewed in Fig. 3, and after passing through said couple, is guided by rolls 42 and 43 to the impres-

sion cylinder 33, about which it passes in counter-clockwise direction. Thence the web is guided by rolls 44, 45, 46, 47 and 48 to a drag roll 49 where it is slit into half webs g^1 and g^2 by means of a slitter roll 50. The half web g^2 is turned under 5 the half web g^1 by means of turnings bars 51 and then the two half webs after being brought into mutual register by compensating rolls 53 are led to the drag roll 54 of the folder J.

A web h is passed through the unit H—N in 10 reverse direction to that of the web g through the unit G—M. In other words, instead of passing about guide rolls 40—41 at the right hand side of the printing couple, it is led about rolls 40a and 41a at the left of the printing couple H. 15 Then after passing between the impression and plate cylinders of the couple H it is led about rolls 45 and 44 to the impression cylinder 33 of the set N passing around said impression cylinder in clockwise direction. Thereafter, it is 20 guided by means of rolls 43, 42, 55 and 56 to a drag roll 57. Here the web h is slit by a slitter roll 58 into half webs h^1 and h^2 and the two half webs after being brought into proper register are led to the drag roll 54 of the folder J. 25

It will be observed that in this arrangement which is shown by full lines in Fig. 3, the multi-color impressions will be found on the under face of the half webs g^1 and g^2 as they enter the folder, while the multi-color impressions will be found on 30 the upper face of the half webs h^1 and h^2 as they enter the folder. If desired, the web g instead of pursuing the lead illustrated by full lines, may pursue the course indicated by broken lines, whereby it passes in reverse direction through the 35 printing couple 30—31 and thence runs clockwise about the impression cylinder 33 of the unit M. On emerging from the unit M, it is carried about rolls 42 and 46 to the drag roll 57, where it is slit with the web h and is assembled therewith in 40 the folder J. As a result of this arrangement the multi-color impressions will be on the upper face of the half webs g^1 and g^2 as they enter the folder.

Similarly, the web h may be run in reverse direction through the unit H—N, as indicated by 45 broken lines, so that the multi-color impressions will be formed on the under side of the half webs h^1 and h^2 as they enter the folder. It will thus be seen that I provide means for impressing the webs individually with color on either face there- 50 of, as desired.

In order to reverse the plate cylinders 31 and the plate cylinders 34, 35, 36 and 37 it is necessary to reverse the inking systems 32 and 38 without reversing the fountain rolls 60 of each printing 55 system. To this end a pair of transfer rolls 61 are provided in each inking system. These rolls are adjustable between the position shown in full lines in the drawing and that shown in broken lines. Each fountain roll 60 and each pick-up roll 60

62 run continuously in one direction, being driven by the usual means (not shown). The distributor rolls 63 and 64 must reverse their direction of rotation with each reversal of the plate cylinder 5 which is inked by them. In one direction of rotation of the plate cylinder the feed of ink is from the pick-up roll 62 through the two transfer rolls 61 in series to the roll 63 and thence by way of rolls 64 to the plate. In the opposite direction of 10 rotation of the plate roll, the feed of ink from the pick-up roll to the roll 63 is effected by only one of the transfer rolls 61, the other being idle. Thus a continuous ink feed is supplied which may be 15 reversed by the transfer rolls to conform to the direction of rotation of the plate roll.

It will be understood that the embodiments of my invention described above are to be taken as 20 illustrative and not limitative of my invention, and that I reserve the right to make such changes in form, construction and arrangement of parts as fall within the spirit and scope of the following claims.

I claim:

1. A printing unit for a web printing press comprising a reversible printing couple having a continuous feed reversible inking system and a reversible multiple printing set also having a continuous feed reversible inking system, and means for leading a web sequentially in either direction 25 through the printing couple and in an opposite direction through the multiple printing set, each inking system including a fountain roll adapted to run continuously in one direction, a distributor roll reversible with the printing couple or set, and means adjustable to maintain a proper transfer of ink between the fountain roll and distributor roll regardless of their relative direction of rotation.

2. A printing unit for a web printing press comprising a reversible printing couple having a continuous feed reversible inking system and a reversible multiple printing set also having a continuous feed reversible inking system, and means for leading a web sequentially in either direction 40 through the printing couple and in either direction through the multiple printing set, each inking system including a fountain roll adapted to run continuously in one direction, a distributor roll reversible with the printing couple or set, and means adjustable to maintain a proper transfer of ink between the fountain roll and distributor roll regardless of their relative direction of rotation.

3. A web printing press comprising a plurality 55 of printing units, each unit comprising a reversible printing couple having a continuous feed reversible inking system and a reversible multiple printing set also having a reversible inking system, each inking system including a fountain roll adapted to run continuously in one direction, a distributor roll reversible with the printing couple or set, and means adjustable to maintain a proper transfer of ink between the fountain roll and distributor roll regardless of their relative direction of rotation, means for guiding a web through each unit and in either direction 60 through the printing couple or printing set of said unit, and means for assembling the webs in superposed relation.

4. A web printing press comprising a plurality 70 of printing units, each unit comprising a reversible printing couple having a continuous feed reversible inking system and a reversible multiple printing set also having a reversible inking system, each inking system including a fountain

roll adapted to run continuously in one direction, a distributor roll reversible with the printing couple or set, and means adjustable to maintain a proper transfer of ink between the fountain roll and distributor roll regardless of their relative direction of rotation, means for guiding a web through each unit and in either direction 75 through the printing couple or printing set of said unit, a folder, and means for assembling the webs in superposed relation and leading them to the folder.

5. A web printing press comprising a plurality of printing units, each unit comprising a reversible printing couple having a continuous feed reversible inking system and a reversible multiple printing set also having a reversible inking system, each inking system including a fountain roll adapted to run continuously in one direction, a distributor roll reversible with the printing couple or set, and means adjustable to maintain 20 a proper transfer of ink between the fountain roll and distributor roll regardless of their relative direction of rotation, means for guiding a web through each unit and in either direction through the printing couple or printing set of 25 said unit, means for slitting each web into a plurality of strips, a folder, and means for assembling the strips and leading them to the folder.

6. A web printing press comprising a plurality of printing units, each unit comprising a reversible printing couple having a continuous feed reversible inking system and a reversible multiple printing set also having a reversible inking system, each inking system including a fountain 30 roll adapted to run continuously in one direction, a distributor roll reversible with the printing couple or set, and means adjustable to maintain a proper transfer of ink between the fountain roll and distributor roll regardless of their relative direction of rotation, means for guiding a web through each unit and in either direction through the printing couple or printing set of 35 said unit, means for slitting each web into a plurality of strips, a folder, and means for assembling the strips in superposed relation and leading them to the folder.

7. A printing unit for a web printing press, comprising a single impression printing set and a multiple impression printing set, each set having a continuous feed inking system, one of said 50 sets and its inking system being reversible, and means for leading a web sequentially through the two sets and in either direction through the reversible set, the inking system of the reversible 55 set including a fountain roll adapted to run continuously in one direction, a distributor roll reversible with the printing set, and means adjustable to maintain a proper transfer of ink between the fountain roll and the distributor roll 60 regardless of their relative direction of rotation.

8. A printing unit for a web printing press, comprising a printing couple and a reversible multiple printing set, means for leading a web sequentially through the printing couple and in either direction through the multiple printing set, the latter having a continuous feed reversible inking system including a fountain roll adapted to run continuously in one direction, a distributor roll reversible with the printing set, and means adjustable to maintain a proper transfer of ink between the fountain roll and distributor roll regardless of their relative direction of rotation.
